United States Patent Office

Des. 187,141
Patented Feb. 2, 1960

187,141

HAND SANDER

Sophocles J. Dokos, Oak Park, Ill., assignor to Sunbeam Corporation, Chicago, Ill., a corporation of Illinois

Application June 22, 1959, Serial No. 56,475

Term of patent 14 years

(Cl. D37—1)

Fig. 3.

Fig. 4.

Fig. 5.

Fig. 1 is a top perspective view of a hand sander embodying my new design;

Fig. 2 is a side elevational view thereof;

Fig. 3 is a top plan view thereof; and

Figs. 4 and 5 are respectively front and rear elevational views.

I claim:

The ornamental design for a hand sander, as shown.
